UNITED STATES PATENT OFFICE.

JOHN BOOTH, OF INDIANAPOLIS, INDIANA.

DESIGN FOR A CHIFFONNIER.

50,091.

Specification for Design.

Patented Dec. 26, 1916.

Application filed September 16, 1916. Serial No. 120,572. Term of patent 7 years.

To all whom it may concern:

Be it known that I, JOHN BOOTH, a citizen of the United States, residing at Indianapolis, Marion county, and State of Indiana, have invented a new, original, and ornamental Design for Chiffonniers, of which the following is a specification, reference being had to the accompanying drawing, forming part thereof.

The figure is a perspective view of a chiffonnier, showing my new design.

I claim:

The ornamental design for a chiffonnier, as shown.

In witness whereof, I have hereunto set my hand and seal at Indianapolis, Indiana, this 26th day of August, A. D. nineteen hundred and sixteen.

JOHN BOOTH. [L. S.]

Witnesses:

A. C. RICE,
H. P. DOOLITTLE.
